HEEL BUILDING MACHINE

John A. McMahon and Ernest D. Sydow,
St. Louis, Mo.

Application May 4, 1942, Serial No. 441,576

11 Claims. (Cl. 12—50)

The general object of this invention is to provide novel heel building mechanism for use in a heel building machine of the character described in our prior application, Serial No. 421,108, filed December 1, 1941, which mechanism is designed to enable said machine to be used in building heel-blanks, either decked, or with straight sides, from pieced lifts; and, if the heel-blank is randed, with pieced rands.

The machine of our said prior application was shown as organized for building relatively high, decked heels for ladies' shoes. In building up the heel-blanks for such heels, only whole lifts are employed, and hence we have shown straight back-bars to be engaged by the heel-blanks as they are moved into position for clamping. Such back-bars are more particularly shown and their function described in our divisional application, Serial No. 430,000, filed February 9, 1942. In accurately positioning the lifts to form a perfectly straight breast on the heel-blank, by causing the breast-plate of the heel-former to force the rounded side, or back, of the heel-blank against the back-bars, there is no danger of any resulting displacement of the lifts, as the pressure is applied in a straight line from the breast to the back of the assembled lifts, and after the heel-blank is clamped, its rear side remains in contact with said back-bars to prevent displacement of the lifts for a part of the distance of travel of the heel-blank around the machine, or until the paste between the lifts has had time to partially set and thus prevent any such displacement after the heel-blank has moved beyond the back-bars.

Pieced lifts are, as a rule, only employed in building heel-blanks for men's shoes, the heels of which are quite large in area as compared with those for ladies' shoes, but of much less height, and for the most part are perfectly flat, with straight sides, although decked heels are sometimes employed. The back-bars of our prior applications referred to are not suitable for use in building heel-blanks from pieced lifts as, when forced against the back-bars by the heel-former and clamped, the heel-blank will invariably show lateral displacement of some of the pieces of the lifts.

It is a principal object of the present invention, therefore, to provide a back-stop for the heel-blanks which will act to shape them or, otherwise, to hold the pieces of the lifts in correct position, as the heel-blanks are forced against it by the heel-former.

Another object of the invention is to provide a

yieldable back-stop which will turn in the direction of movement of the clamped heel-blank as the latter is carried forward by the endless clamp-carrier, and which will be automatically returned to its normal position after the clamped heel-blank has passed out of engagement with it.

Another object of the invention is to provide a back-stop of the character described composed of a series of superimposed back-stop plates adapted to be mounted in a holder, which plates may be built up to any desired height corresponding to the height of the heel-blanks being built, and which may be arranged in stepped formation, as in the case of the back-bars of our prior applications, where decked heel-blanks are being built.

The back-stop is provided with a shaping recess, preferably V-shaped, so that when the rounded side of the heel-blank is forced into the crotch, the abutting edges of the pieces of the lifts will be forced together by engagement with the converging sides thereof. If superimposed back-stop plates are employed, each plate will be V-shaped at one end so that they may either be assembled to form straight, converging side walls or, if decked heel-blanks are being built, to provide a stepped formation. In either form the back-stop is adjustable toward and from the heel-former.

30 In the drawings—

Fig. 1 is a plan view of a machine embodying our invention, the bin for containing the lifts to be pasted, assembled and clamped being omitted for clearness of illustration;

35 Fig. 2 is a view in front elevation of the central portion of the machine, with a portion of the bin shown mounted thereon;

Fig. 3 is a similar view in rear elevation;

Fig. 4 is a view in front elevation, on an enlarged scale, of the heel-building and delivering mechanism, the clamping mechanism appearing at the rear being broken off;

Fig. 5 is a vertical sectional view on the line 5—5 of Fig. 4;

40 Fig. 6 is a horizontal section on the line 6—6 of Fig. 4 and Fig. 5;

Fig. 7 is a horizontal section on the line 7—7 of Fig. 4 and Fig. 5;

45 Fig. 8 is a plan view, on an enlarged scale and partly in section, of the front central portion of the machine, showing a randed pieced heel-blank in position to be advanced into engagement with our novel back-stop;

50 Fig. 9 is a similar view showing the heel-blank

in engagement with the back-stop and in position to be clamped;

Fig. 10 is also a similar view, showing the back-stop turned to one side by the clamped heel-blank as it is moved forward by the endless clamp carrier;

Fig. 11 is a broken plan view, on an enlarged scale and partly in section, showing the spring control for the pivoted back-stop holder;

Fig. 12 is a longitudinal on the line 12—12 of Fig. 9 showing the clamping plate lowered into clamping position on the randed heel-blank;

Fig. 13 is a vertical sectional view on the line 13—13 of Fig. 3;

Fig. 14 is a vertical sectional view on the line 14—14 of Fig. 3;

Fig. 15 is a vertical sectional view on the line 15—15 of Fig. 3;

Fig. 16 is a vertical sectional view on the line 16—16 of Fig. 3;

Fig. 17 is a vertical sectional view on the line 17—17 of Fig. 1;

Fig. 18 is an assembled view, showing in perspective the three parts composing an unitary back-stop assembly;

Fig. 19 is a plan view of the base lift of a heel-blank;

Fig. 20 is a similar view showing the sections of a two-piece lift;

Fig. 21 is a similar view of the sections of a two-piece rand;

Fig. 22 is a view similar to Fig. 9, but showing a decked heel-blank in engagement with a modified construction of back-stop;

Fig. 23 is a sectional view taken on the line 23—23 of Fig. 22;

Fig. 24 is a cross-sectional view on line 24—24 of Fig. 23; and

Fig. 25 is a perspective view of one of the plates used in our modified back-stop of multiple construction.

Referring now to the drawings, the numerals 3, 4, Figs. 1, 2 and 3 indicate, respectively, side frame members of the machine, in suitable bearings in which is mounted a main drive shaft 5, on one end of which is secured a pulley 6 which is driven by a belt 7 from a source of power (not shown). Beside pulley 6 is mounted on the shaft a loose pulley 8, a belt shifter 9 being employed to shift the belt from one pulley to the other, according to whether the machine is to be driven, or its motion stopped. Mounted on the drive shaft 5 near its opposite end is a clutch 10, comprising a loose clutch member 11 and a fast clutch member 12. The numeral 13 indicates a foot treadle to be actuated at will by an operator, which is secured at its inner end on a rock shaft 14 pivotally supported in hangers 15 depending from a cross-bar 16 secured at its ends to the frame members 3, 4, of the machine. Also secured on rock-shaft 14 adjacent the head of treadle 13 is a rocker-arm 17 extending downward from the rock-shaft, and pivotally connected at its lower end to one end of a connecting bar 18, the other end of which is secured to a depending rocker-arm 19, the upper end of which is secured to a rock-shaft 20 supported in bearings in the frame members 3, 4. The lower end of rocker-arm 19 is pivotally connected to one end of a connecting bar 22, the other end of which is pivotally connected to the lower end of a rocker-arm 23, which depends from and is integral with a circular cam member 24 (Figs. 3 and 13), the outer face of which is provided with cam surfaces working against supplemental

cam surfaces on a fixed cam member 26 mounted on the frame of the machine. The cam member 24 is loosely mounted on the drive shaft 5 and abuts against the hub 27 of a sprocket gear 28, said hub and gear being loose on shaft 5. When the treadle 13 is depressed, the connecting bar 18 is moved to the rear, moving the rocker-arm 19, connecting bar 22 and rocker-arm 23 in the same direction. This movement causes the cam member 24 to be rotated and its cam surfaces to ride over the complementary cam surfaces on the fixed cam member 26, thereby moving its hub 27 into engagement with the side of the sprocket gear 28 and moving the latter inward, or toward the right in Fig. 3, causing the loose clutch member 11 to be moved into frictional engagement with the fast clutch member 12, which is constantly rotated by the drive shaft 5. The loose clutch member 11 and the sprocket gear 28 have a common hub 29, so that when the loose clutch member is rotated by engagement with the fast clutch member 12 the sprocket gear 28 will be caused to be rotated. Secured on a cross-shaft 30 (Fig. 13), supported in bearings on the frame members 3, 4, is a sprocket gear 31, considerably larger in diameter than the sprocket gear 28, and which is operatively connected to the latter by means of a sprocket chain 32. Secured on the inner side of the sprocket 31 is a small sprocket wheel 33 (Fig. 14). Located above the cross-shaft 30 and rotatably mounted in bearings in the frame members 3, 4, is a cam shaft 34 on which is loosely mounted a relatively large sprocket wheel 35 which is operatively connected to the sprocket wheel 33 by a sprocket chain 36. Mounted on this cam shaft 34 are a number of cams, which are brought into operation in a given order, so that when the cam shaft is rotated the various operations of the machine will be caused to occur in a given sequence. As the operation of all of these cams is fully described in our prior parent application, only those cams, to be later referred to, which operate the mechanisms involved in the invention to which the present application is directed will be referred to in this specification.

The numeral 37 (Fig. 13) indicates a coil spring, one end of which is secured to the rock shaft 14 and the other to the rocker-arm 19. In the operation of the machine, the treadle 13 is held in a depressed position only momentarily and when released, the spring 37, which had been placed under tension when the treadle was depressed, operates to return the treadle and the cam faces on cam member 24 to normal position, thereby permitting the loose clutch member 11 to separate from the fast clutch member 12. The return movement of the treadle 13 is arrested by an adjustable stop screw 38 which is adapted to be engaged by the lower end of rocker arm 19. The fixed cam member 26 may be secured in adjusted positions by means of a simple clamp 39 (Fig. 3).

Referring more particularly to Figs. 4, 5 and 8, the heel lifts 40 are first pasted and then assembled on a base plate 41 with their breast portions inserted between two sets of heel-forming plates 42, 42, mounted one upon the other in holders 43 and clamped therein by means of set screws 44. In building up a heel-blank according to the present invention, whether of the decked or straight-sided type, the lifts are assembled in order from the bottom, or tread portion, to the upper portion, or base, of the heel.

To enable either type of heel-blank to be built up on our machine, each of the heel-forming plates 42 is provided at its inner end with a portion 42^a which serves as a breast plate, and with inward-extending projections 45 which, in the assembled condition, when decked heels are being built, diverge from each other in an upward direction, as fully illustrated and described in our prior applications. If straight-sided heel-blanks are being built, the inner edges of these projections will lie flush with each other. In either case the projections form a recess 42^b corresponding to the shape of the heel at the sides of the breast. The holders 43 are mounted on the inner end of a movable support 46 which is mounted to slide in guides 46^a over the top of the base plate 41. The support 46 carrying the holders 43 with the heel-forming plates 42 clamped therein will hereinafter be referred to as a heel-former. After a heel-blank has been assembled on the base plate 41, the first operation that occurs upon depressing treadle 13 is the movement of the heel-former inward to carry the assembled heel-blank into position on a travelling heel-clamp carrier 47, an endless series of such carriers being shown in Fig. 1, and the mechanism for effecting this operation will now be described.

Secured on cam shaft 34 (Fig. 16) is a cam 48 having a cam groove 49 formed in the face thereof. Pivoted at its lower end on the shaft 30 is an actuating lever 50 the upper end of which is pivotally connected at 51 to the inner end of a connecting rod 52, the other end of which is pivotally connected at 53 (Fig. 5) to the lower end of a crank-arm 54, the upper end of which is secured on a rock-shaft 55 mounted in bearings 55^a provided on vertical frame members 55^b at the front of the machine. A second crank-arm 54^b is similarly secured on rock-shaft 55 and its upper end is pivotally connected to one end of a link 56, the other end of which link is pivotally connected to a lug 57 carried by and projecting downward from the bottom of the support 46. As the cam shaft 34 is rotated through the medium of sprocket 35 and sprocket chain 36 from the sprocket 33, as previously described, the cam 48 will be turned. Mounted on the actuating lever 50 is a roller 58 which engages in the cam groove 49, and as the high part of this cam groove passes over the roller 58 the actuating lever 50 will be moved toward the front of the machine, thereby partially rotating the rock-shaft 55 and through the medium of crank-arm 54^b and link 56 moving a heel-former inward and the heel-blank from the base plate 41 onto the bottom of the clamp carrier 47. In the continued revolution of cam 48, the low part of cam groove 49 will engage roller 58 and return the heel-former to the normal position shown in Fig. 5. Just prior to the return movement of the heel-former the machine operates to clamp the heel-blank deposited on the clamp carrier 47, and the means for effecting this clamping operation will now be described, referring particularly to Figs. 5 and 15.

Pivotedly mounted on a cross-shaft 59 located at the rear part of the machine is a lever arm 60 which extends well toward the front of the machine and at its inner end is bifurcated (Fig. 1), the two arms 61 of this bifurcated end being connected, respectively, at 62 to the upper ends of two links 63 located on opposite sides of a plunger 64, and being connected at their lower ends to a cross-pin 65 passing through said plunger. The plunger 64 is slidably mounted in bearings 66 on

the frame of the machine. Secured on the cam shaft 34 is a cam 67 the peripheral face of which normally engages a wear plate 68 secured on the under side of the lever arm 60. As the cam 67 rotates, its high point passing under and in engagement with wear plate 68 raises the lower end of lever arm 60 which in turn, through links 63, raises the plunger 64, which operates to actuate the clamping mechanism by the following means: 5 A rack-bar 69 (Fig. 5) slidably mounted in guides 70 engages a spur gear 71 mounted in bearings 72. A companion rack-bar 73 slidably mounted in guides 74 engages the spur gear 71 on the opposite side to that engaged by rack-bar 69. 10 An interiorly screw-threaded boss 75 on rack-bar 69 receives the lower screw-threaded portion of a rod 76, which is located above and in line with the plunger 64, so that when the latter is raised, as described, its upper end will engage the lower end of rod 76 and raise it, thereby raising rack-bar 69 and lowering rack-bar 73. The latter, as will presently appear, is provided with means for engaging and moving the clamping mechanism into clamping position on a heel-blank. 15 20 25 Each of the heel clamp carriers previously referred to is provided on its under side with rollers 77, which run on tracks 78 supported on the frame of the machine, and which extend entirely around the machine, as shown by Fig. 1. These clamp carriers are pivotally connected together in a manner to form an endless conveyor. Slidably mounted in the sides of each clamp carrier are two parallel bars 81 which are connected at their upper ends by a cross-bar 82 and at their lower ends by a cross-bar 83, thus providing a slidable clamping frame. Secured at their upper ends in, and projecting well below the under side of each carrier 47, are two parallel rods 84, which are connected at their lower ends by a cross-bar 85. Formed integral with the cross-bar 83 at each end thereof, respectively, are two sleeves 86 which are slidably mounted on the rods 84. Loosely mounted in the cross-bar 82 of each carrier is a pin 87, the head 88 of which is adapted to be engaged by the upper side of cross-bar 82 when the clamping frame is raised. Pivotally mounted on the lower end of pin 87 is a clamp plate 90, between which and the under side of cross-bar 82 is interposed a coil spring 91. The clamp plate 90 is of the type described and claimed in the patent to Dennis Parks, No. 2,176,560, dated October 17, 1939, and when forced downward into engagement with the base of the heel-blank, indicated in the views where shown by the letter H, its construction is such as to enable it to engage the hollowed-out portion of the base lift formed, as usual by gouging, or the similar depression produced by applying a rand to the base lift, such engagement occurring at the breast of the heel-blank and operating to afford a firm engagement of the clamp plate with the entire surface of the base lift. At the same time, the clamp plate will make a flush engagement with a perfectly flat base, as in clamping heel-blanks for men's shoes.

Secured at its upper end on the under side of each clamp carrier 47 is a rack-bar 97, which at its lower end is secured in the cross-bar 85. Projecting downward from the cross-bar 83 are two short parallel arms 98 between which is rotatably mounted a pinion 99 on a cross-pin 100. Pivotally mounted between arms 98 at their lower ends is a ratchet 101 which normally engages the teeth of pinion 99 and is yieldingly held in such engage-

ment by a spring 102, shown in Fig. 12 and also in Fig. 5, engaging a tail piece 104 on said ratchet. Assuming the operator has built up a heel-blank on base plate 41, he depresses foot treadle 13, and through the operations of the mechanisms previously described places cam shaft 34 in operation. Cam 48 on said shaft now operates to cause the heel-former to be moved inward from the position shown in Fig. 5 and deposit the heel-blank on one of the clamp-carriers 47 which, in the operation of the machine has been brought to rest immediately in front of the heel-former. Cam 67 (Fig. 15) now operates to raise the outer end of lever arm 60, which by means of links 63 raises plunger 64 into engagement with the lower end of rod 76 and raises it, and with it the rack-bar 69, causing rack-bar 73 to be moved downward. Projecting outward from the upper end of this rack-bar is an arm 105 which extends over the cross-bar 83 and normally at some distance above the same, as shown by Fig. 5, and in the downward movement of rack-bar 73 engages said cross-bar and draws the bars 81 and cross-bar 82 downward to carry the clamp plate 90 into engagement with the upper side of the heel-blank and then to place spring 91 under tension to cause it to exert the proper pressure on the clamp plate. Ratchet 101, which rode over the teeth of pinion 99 as the latter was rotated by engagement with the teeth of rack-bar 97 in the downward movement of the clamping frame, now engages behind a tooth of the pinion and prevents the latter from being rotated in the opposite direction and thus securely locks the clamp in its clamped position.

The screw-threaded rod 76 is vertically adjustable in the boss 75 by means of a thumb-screw 230 (Figs. 2 and 3) on its upper end, to regulate the throw of the clamp plate 90 in accordance with the height of the heel-blank being built. A gauge 231 provided with numbered graduations, in conjunction with an indicator 232 on the rod, enables the operator to properly adjust rod 76 relative to the plunger 64. Fig. 12 shows the open, or raised, position of clamp plate 90 in dotted lines, in which the operating parts would be in the position shown in Fig. 5, and its clamped position on a heel-blank in full lines. The latter position of the clamp plate is also shown in Fig. 23. Immediately after the descent of the clamp plate on the heel-blank, the low part of cam 48 will pass over roller 58 and cause the heel-former to be returned to the position shown in Fig. 5. As each heel-blank is clamped, it is moved forward in the operation of the machine a distance sufficient to bring an empty clamp carrier opposite the base plate 41, while at substantially the same time a clamped heel-blank, which has traveled around the entire machine in order to give the paste between the lifts time to set, and arrived at a discharge point, or chute, 106 (Fig. 1), will be released and ejected from its clamp carrier immediately beyond the empty carrier moved into position, the clamp carrier from which the heel has been discharged becoming the empty carrier next to receive a heel-blank. All the operations of the machine occur in stages, and while the clutch members 11 and 12 are momentarily held in engagement by depression of treadle 13. However, the time interval between the various operations is very slight, depending upon the setting of the cams on the cam shaft, and in some instances, as in the clamping of a fresh heel-blank and the discharge of a dried, or completed, heel, the two ac-

tions occur almost simultaneously. The mechanism for effecting the travel in stages of the endless series of clamp carriers will now be briefly described, as this mechanism, of itself, forms no part of the present invention, being fully described and claimed in our parent application referred to.

Referring to Fig. 1, the machine is provided at opposite ends with two upright stub shafts, 107, 108, respectively, and rotatably mounted thereon are two large sprocket wheels 109 and 109^a, respectively, which are provided in their peripheries with equidistant recesses 110 which engage lugs on the corners of the clamp carriers 41, these pivotally-connected carriers thus forming an endless-chain carrier, or conveyor. Fixedly secured to the hub of each sprocket wheel is a ratchet wheel 111, from each of which projects a crank-arm 112, the outer ends of these crank-arms being connected to opposite ends of a connecting rod 113, which is provided with a cam surface 114. Mounted on each of the crank-arms 112 is a spring-pressed ratchet 115. Projecting inward from connecting rod 113 is an arm 118 to which are secured the ends of two coil springs 119, the opposite ends of which are secured to a fixed arm 120 on a frame member 121. Pivotally mounted on member 121 is a stop-arm 122 provided on its outer end with a roller 123 which is normally pressed toward the periphery of wheel 109 by a spring 124. Normally, roller 123 rests in one or the other of the recesses 110 of wheel 109, in which position it stops the rotation of the wheel, and hence the movement of the endless series of clamp carriers. On the under side of stop-arm 122 is a roller 126 which is adapted to be engaged by the cam surface 114 to raise stop-arm 122 and release roller 123 from engagement with a recess 110 to permit wheel 109 to be rotated. The rotation of wheel 109 is effected as follows:

Secured on the cam shaft 34 is a cam 150 (Figs. 1 and 16) and below this cam is a lever-arm 151 which is pivotally mounted at its inner end on a front frame member of the machine. Mounted on the upper side of this lever-arm is a wear plate 152 which, when the cam shaft 34 is rotated, will be engaged by the high portion of cam 150 and cause the outer end of arm 151 to be depressed. Pivotally connected at its lower end at 153 to the outer end of lever arm 151 is a pull rod 154, which at its upper end is pivotally connected at 155 (Figs. 15 and 17) with one arm 156 of a bell-crank lever 157, pivoted at its elbow at 158 on the lower end of a frame support 159. The other arm 160 is pivotally connected at its upper end to one end of a link 161 the other end of which is pivotally connected to a boss 162 secured on the connecting rod 113. As the cam shaft 34 rotates, the high point of cam 150 will engage wear plate 152 and force the outer end of the lever arm 151 downward, causing pull rod 154 to turn bell-crank lever 157, and move connecting rod 113 to the left (Fig. 1). In this movement of the connecting rod ratchets 115 will be moved by crank-arms 112 over the teeth of ratchet-wheels 111 and finally engage behind one of said teeth. This movement of the connecting rod places coil springs 119 under tension by extending them, and at the same time causes cam surface 114 thereon to ride under roller 126 and raise stop-arm 122, disengaging its roller from a recess 110 in sprocket wheel 109. When the low point of cam 150 reaches wear plate 152, the power stored in springs 119 by the previous movement

will be exerted to move connecting rod 113 to the right, thereby, through the ratchet mechanism described, turning the wheels 109 and 109^a clockwise and causing the movement in the same direction of the endless series of clamp carriers. The movement to the right of connecting rod 113 also acts to release stop-arm 122, which is forced downward by its spring to enable its roller 123 to engage in a recess 110 in sprocket wheel 109 succeeding that in which it had previously rested, and thus stop the rotation of the sprocket wheels and movement of the endless carrier. The cam shaft 34 is, of course, rotated through a single cycle with each depression of treadle 13, and this rotation is initiated and stopped through the medium of automatic clutch and stop mechanism, indicated generally by the numeral 139 in Figs. 1 and 14, which is governed by a clutch-control bar 132, actuated from rock-shaft 20. This clutch mechanism is fully described in our parent application referred to, and as it forms no part of the present invention, it is not deemed necessary to more particularly illustrate and describe the same, as automatic clutches for producing single revolutions of a driven shaft are well known, and any such conventional clutch, placed in operation on depressing treadle 13, could be employed.

In the operation of the machine in building heel-blanks, the movement and stoppage of the endless carrier above described will have brought a clamped and dried heel-blank to rest opposite the opening to the chute 106 (Figs. 1 and 2) where it is to be unclamped and discharged. The unclamping and ejecting mechanisms are not illustrated or described in the present case, as they are not involved in the invention claimed herein, are fully illustrated, described and claimed in the parent application, and their operations are not necessary to the performance of the present invention.

We will now describe our novel back-stop mechanism for positioning and holding in position the pieced lifts and, if used, the pieced rand of a heel-blank when the heel-blank is moved into position to be clamped, and during the clamping operation.

Referring to Fig. 1, there is mounted on a support, or table, 205 at the front of the machine a paste applying device 206 of any preferred construction, but as here shown having a lower roller 207 and an upper roller 208 between which the lifts are passed to receive paste in a well known manner. The lower roller rotates in a paste pot 209 and supplies paste to the upper roller, the paste being maintained in fluid condition by an electric heater (not shown) supplied with current by a conductor 210. The roller 207 is rotated by a belt drive 211 from shaft 5, or in any other desired manner. As each lift is passed between the rollers of the paste applying device to be supplied with paste it is positioned in the heel-former by the operator with its breast against the heel-forming plates 42 and its sides against the respective projections 45. In the present case, this applies only to the base lift 212 shown in Fig. 19. When this lift has been pasted and positioned as described, two layers of pieced lifts 213, Fig. 20 are then superimposed upon the base lift in a manner to break joints with each other, as well known in the art and as indicated by dotted lines in Figs. 8 and 9. A two-piece rand 214, after pasting, may then be applied to the assembled lifts, and the heel-blank thus formed is ready to be moved onto a

clamp carrier to be clamped by the plate 90, in the manner previously described.

We will now describe the means we employ for securing great accuracy in the conformation, or shape, of a heel-blank made of pieced lifts while at the same time preventing displacement of the lifts, or of any of them, while positioning a heel-blank for clamping, and during the act of clamping the same, referring particularly to Figs. 8 to 12, and Fig. 18.

Rotatably mounted on and extending through a frame support 215 is a post 216 (Figs. 11, 12 and 18) having on its upper end an integral block 217, the top side of which is grooved to provide a recess, or seat, 218 having parallel side walls 219, the bottom of the recess being provided in its central portion with a screw-threaded hole 220. Firmly secured on the lower end of post 216 below the support 215 by a set screw 221 is a ring 222 which is provided with a laterally projecting pin 223. Secured at one end in the outer end of this pin is a coil spring 224, the other end of which is secured to a fixed pin 225 on the frame. This spring normally holds the right-hand side (Figs. 8 and 9) of block 217 against a stop 226, which may be of the adjustable, or dash-pot type. The back-stop proper (Fig. 18) comprises a flat shank 227 having a longitudinal slot 228 and provided at one end with two integral arms 229 diverging at right-angles to each other, and forming a crotch for receiving the rounded side, or back, of the heel-blank, as shown in Fig. 9. With the post 216 secured in ring 222, the shank 227 is then seated in the recess 218 and a binding screw 240 is passed through slot 228 and screwed into the hole 220. As will be apparent from an inspection of Figs. 8 and 9, by loosening the binding screw 240 the back-stop can be adjusted toward or from the heel-former so as to position it to properly meet the heel-blank as it is moved inward to clamping position, thus enabling the back-stop to be engaged by and properly position any size of heel-blank that may be built on the machine. From an inspection of these figures, it will also be seen that the center of the crotch of the back-stop coincides with the median line of the heel-blank built up in the heel-former, so that when the latter is moved inward to carry the heel-blank into engagement with the back-stop, or to the position shown in Figs. 9 and 12, the rounded sides of the pieced lifts will engage in the crotch formed by the arms 229 causing the pieces to be forced together, while at the breast of the heel-blank the lift pieces will be held in position by the projections 45 of the heel-forming plates and be correctly aligned by being forced against the breast plates 42^a. With the heel-blank thus positioned and the pieces of the lifts held from displacement, the clamping plate 90 is then lowered to clamp the heel-blank, as illustrated in Fig. 12, in the manner previously described. Immediately after the clamping operation, the endless series of clamp carriers is automatically moved to the left, as indicated by the arrows in Figs. 1 and 10, respectively, to bring an empty clamp carrier opposite the heel-former, and in this movement, the back-stop will swivel on the post 216 and be turned in the same direction to permit the clamped heel-blank to pass beyond it, as shown by Fig. 10, after which it is returned to the normal position shown by Fig. 8 through the action of spring 224.

The arrangement just described, comprising a single, or unitary back-stop, adjustably mounted

in a block, or holder, would generally be employed only when the heels being built were straight-sided and of uniform height, consisting, as a rule, of a base lift, two layers of pieced lifts, and a superimposed rand, such heels being used only on men's shoes. In place of using a rand, the lift at the top of the heel-blank may be gouged out, as well known in the art. However, heels of a greater height than indicated above are often made for men's shoes; likewise, decked heels for men's shoes are sometimes made of pieced lifts; and to make the machine applicable for building either type of heel-blank, the modified construction of back-stop illustrated in Figs. 22 to 25 may be advantageously employed, and will now be described.

The numeral 241, Fig. 24, indicates a hollow, rectangular holder having a post 242 on its bottom which is adapted to be secured in the ring 222 in the same manner as the post 216, and being rotatably mounted in the support 215. At its top, the holder is provided with a binding screw 233. The back-stop proper, in this case, is made up of a series of superimposed, flat back-stop plates, one of which is shown in Fig. 25. Each of these back-stop plates comprises a rectangular shank 234 having at one end arms 235 diverging from each other at right-angles, as in the case of the unitary back-stop previously described. In using this back-stop, the shanks of a number of plates to build a back-stop of the desired height are inserted in the holder 241, and if a decked heel is to be built, the plates are arranged in stepped formation, as illustrated in Figs. 22 and 23, to correspond to the conformation of the back, or rounded side, of the heel-blank. The plates are then clamped in position by the binding screw 233. The heel-forming plates 42 would also be similarly arranged, to correspond to the shape of the heel-blank at the sides of the breast portion, as fully described in application No. 430,000. After the built-up heel-blank has been moved into engagement with the back-stop, and the clamping plate 90 lowered to clamp it, as illustrated in Fig. 23, when the endless series of clamp carriers is placed in motion the composite back-stop described will swivel on the support 215 to permit the clamped heel-blank to pass beyond it, in the same manner as previously described.

An important advantage of this modified construction of back-stop is that it may readily be made adaptable to any height or shape of heel-blank. Thus, if a heel-blank of less height than that illustrated in Fig. 23 is to be built, the binding screw 233 would be loosened, the appropriate number of back-stop plates moved back, or to the right in Fig. 23, to reduce the engaging surface of the back-stop, or its crotch portion, to the desired height, when the screw would again be tightened. Again, if a straight-sided heel-blank is to be built, the back-stop plates would be adjusted so that the inner sides of the superimposed series of arms 235 would lie flush with each other to provide flat, vertical engaging surfaces for the rounded side of the heel-blank.

For convenience of the operator, we mount above the machine a bin 236 open at its front side and provided with a number of compartments 237 for holding lifts of the various sizes required in building a particular type of heel. This bin is mounted on columns 238 supported on the frame of the machine.

We wish it to be understood that the inven-

tion is not limited to the exact details of construction herein described and illustrated in the drawings, except as may be required by certain of the appended claims, and that various changes may be made in the construction, arrangement and operation of the machine, or of its elements, without departing from the spirit of the invention.

We claim:

1. In a heel-building machine, in combination with a reciprocable heel-former, a swivelled back-stop in line therewith having a shaping recess, means for reciprocating said heel-former to bring the rounded side of a heel-blank built against the same into engagement with the walls of said recess, means for clamping the heel-blank while so positioned, and means for moving the clamped heel-blank beyond the line of movement of the heel-former, thereby turning the back-stop to one side to permit the heel-blank to clear the same.

2. In a heel-building machine, in combination with a reciprocable heel-former, a swivelled, spring-controlled back-stop in line therewith having a shaping recess, means for reciprocating said heel-former to bring the rounded side of a heel-blank built against the same into engagement with the walls of said recess, means for clamping the heel-blank while so positioned, and means for moving the clamped heel-blank beyond the line of movement of the heel-former, thereby turning the back-stop to one side to permit the heel-blank to clear the same.

3. In a heel-building machine, in combination with a reciprocable heel-former, a spring-controlled, swivelled holder mounted on the machine, a back-stop adjustably mounted in said holder in the line of movement of said heel-former and having a V-shaped recess, and means for reciprocating said heel-former to bring the rounded side of a heel-blank built against the same into engagement with the walls of said recess.

4. In a heel-building machine, in combination with a reciprocable heel-former having a recess for receiving and positioning the breast portion of an assembly of lifts, a spring-controlled, swivelled holder mounted on the machine, a back-stop adjustably mounted in said holder in the line of movement of said heel-former and having a V-shaped recess, means for reciprocating said heel-former to bring the rounded sides of said lifts into engagement with the walls of said V-shaped recess, means for clamping the assembly of lifts while so positioned, and means for moving the clamped assembly of lifts beyond the line of movement of the heel-former, thereby turning the back-stop to one side to permit the clamped lifts to clear the same.

5. In a heel-building machine, in combination with a reciprocable heel-former, a back-stop in line therewith having a recess adjustable as to height and configuration, and means for reciprocating said heel-former to bring the rounded side of a heel-blank built against the same into engagement with the walls of said recess.

6. In a heel-building machine, in combination with a reciprocable heel-former, a back-stop in line therewith comprising a series of plates having corresponding diverging arms at one end superimposed upon each other to the height of the heel-blank to be built and providing a shaping recess, means for adjusting said plates longitudinally of each other to produce

a desired configuration of the walls of said recess, and means for reciprocating said heel-former to bring the rounded side of a heel-blank built against the same into engagement with the walls of said recess.

7. In a heel-building machine, in combination with a reciprocable heel-former having a recess, variable as to height and configuration, for receiving and positioning the breast portion of an assembly of lifts forming a heel-blank, a back-stop in line with said heel-former having a shaping recess also variable as to height and configuration, and means for reciprocating said heel-former to bring the rounded side of a heel-blank built against the same into engagement with the walls of said recess.

8. In a machine for building heelblanks of pieced lifts, in combination with means for clamping the heel-blanks comprising a plurality of travelling carriers movable in stages and each of which has clamping mechanism mounted thereon, a swivelled back-stop located beyond the line of movement of the clamping mechanism and presenting a V-shaped recess to the heel-former, a reciprocable heel-former movable with a built-up heel-blank to bring the latter under the clamping mechanism of a carrier at rest and its rounded side into engagement with the walls of said recess to force the edges of the pieced lifts together, and means controlled by the operator for operating said heel-former and the clamping mechanism of the stationary carrier in the order named, and for advancing thereafter all of said carriers a single stage, thereby turning the back-stop to one side to permit the clamped heel-blank to clear the same.

9. In a mechanism of the kind described, a movable support for a plurality of superposed heel lifts, a stop against which the heel lifts may be abutted, said stop having walls with a positioning opening, said walls providing an aligning means against which the lifts may be forced and by which they may be aligned, said walls being unyieldable in the direction of the

force during the aligning operation, means for moving the movable support in a direction lateral to the aligning force, the walls extending to provide an obstruction to such lateral movement of the lifts engaged by them, and means supporting the walls for lateral movement in a direction to permit said lateral displacement of the support and the lifts thereon.

10. In a mechanism of the kind described, a movable support for a plurality of superposed heel lifts, a stop having walls extending on opposite sides of a medial axis of the lifts, against which the lifts may be forced by force applied along said axis, to align the superposed lifts relative to each other, means moving the movable support in a direction lateral relative to the direction of force, means supporting the stop against displacement in said direction of force, said stop supporting means including yieldable means normally to maintain the walls of the stop in lift receiving position, but adapted to yield to provide lateral movement of the walls in a direction to permit lateral passage of the lifts with the movable support.

11. In a mechanism of the kind described, a movable support for a plurality of superposed heel lifts, a stop having walls providing an opening of predetermined fixed shape, said walls being adapted to receive superposed heel lifts and be engaged by said lifts on opposite sides of an axis thereof, and to align said lifts upon application of force thereto along said axis, means to move the movable support in a direction lateral to said axis, means to support the stop against displacement in the direction of said force during the aligning operation, said means providing lateral displacement of the stop to permit passage of the lifts upon movement of the movable support, spring means opposing said lateral movement and being adapted to return the stop toward its aligning position, and arresting means to arrest the return movement of the stop when it attains aligning position.
